US0D1014676S

(12) **United States Design Patent** (10) **Patent No.:** **US D1,014,676 S**
(45) **Date of Patent:** **** Feb. 13, 2024**

(54) **GOLF CLUB HEAD**

(71) Applicant: **PARSONS XTREME GOLF, LLC**,
Scottsdale, AZ (US)

(72) Inventor: **Caleb S. Kroloff**, Phoenix, AZ (US)

(73) Assignee: **PARSONS XTREME GOLF, LLC**,
Scottsdale, AZ (US)

(**) Term: **15 Years**

(21) Appl. No.: **29/839,383**

(22) Filed: **May 20, 2022**

Related U.S. Application Data

(60) Division of application No. 29/756,882, filed on Oct. 30, 2020, now Pat. No. Des. 956,899, which is a continuation-in-part of application No. 29/752,556, filed on Sep. 28, 2020, now abandoned.

(57) **CLAIM**

The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1; FIG. 6 is a bottom view of the golf club head of FIG. 1; FIG. 7 is a left side view of the golf club head of FIG. 1; and, FIG. 8 is a right side view of the golf club head of FIG. 1. The broken lines shown on the drawings form no part of the claimed design.

1 Claim, 4 Drawing Sheets
